INDICATING LAMP RECEPTACLE

Alric H. Powell, Yeadon, Pa., assignor to General
Electric Company, a corporation of New York

Application July 23, 1941, Serial No. 403,635

6 Claims. (CL 177—329)

My invention relates to an indicating lamp receptacle and more particularly to a pilot lamp receptacle for use on panel boards.

In many cases, panel boards are provided with indicating or pilot lamps, visible from the front of the board, which give an indication as to whether or not circuits concealed behind the board are energized. Such pilot lamps are of low voltage and power consumption and are connected to the energized circuits in series with a resistor. This requires a special receptacle to mount the lamp in indicating position and to support the resistor.

It is an object of my invention to provide an improved receptacle for mounting an indicating lamp and associated resistor on a panel board.

It is another object of my invention to provide an improved receptacle for panel board mounting which comprises relatively few parts, is easily assembled and manufactured at low cost.

A further object of my invention is the provision of an improved receptacle for panel mounting in which a single supporting element is utilized to support the associated resistor and indicating lamp on the panel.

In the accompanying drawing, Fig. 1 is a perspective view of my indicating lamp receptacle; Fig. 2 is a sectional view through the device; Fig. 3 is a sectional view taken along line 3—3 of Fig. 2; Fig. 4 is a sectional view taken along the line 4—4 of Fig. 2; Fig. 5 is a perspective view of one of the terminal contacts, and Fig. 6 is a diagrammatic view showing the indicating lamp connected to an energized circuit.

Referring to Fig. 6 of the drawing, a pilot or indicating lamp L and a resistor R are shown in diagrammatic form as connected in series across line conductors C, the energization of which is to be indicated on the panel board. Whenever the conductors C are energized, the lamp L will be lighted. The lamp L is visible from the front of the panel board which conceals the conductors C and the resistor R and at the same time protects it from possible damage. The lamp and resistor are carried by a receptacle mounted on the panel board.

Referring to Fig. 2 of the drawing, my receptacle includes a support 1 which is in the form of a metal tube threaded throughout the entire length of its external surface, as indicated at 2. At one end, the tube is closed by a cap 3 which may be formed of any suitable insulating material, such as a molded plastic, and which is threaded on the end of the tube, as indicated

at 4. The threads 4 are formed in the outer wall of an annular recess 5 which is formed adjacent a sleeve 6 extending inwardly into the interior of the tube. Extending through spaced openings 7 in the end cap 3 are spaced contact members 8 receiving the indicating lamp L.

Each contact member 8 comprises an elongated strip of flexible material, such as spring bronze, one end of which is provided with a projecting portion 9 for engaging the lamp while the other end is bent in the form of a U 10 which receives a screw 11 to form a terminal means for the contact blade. Each contact blade (Fig. 5) is also provided with a laterally extending tongue 12. In mounting the contact blades in position on the end cap 3, the lamp-engaging ends of the blades are inserted through the openings 7 and the blades are pushed through the openings until the tongues 12 snap into a recess 13 formed centrally of the sleeve 6. Once the contact blades are seated in position on the end cap, they cannot be dislodged therefrom due to the fact that the tongues 12 engage a wall 14 of the recess 13, preventing the contact blades from being removed lengthwise from the end cap. Movement of the contact blades in the opposite direction is prevented by shoulders 15 which engage the walls of the cap adjacent the openings 7. Those portions of the contact blade which extend beyond the confines of the tube 1 and cap 3 are held firmly in assembled position by being seated in grooves 16 formed in an extension 17 of the end cap 3.

The contact surfaces 9 of the blades cooperate with contact ferrules 25 formed in the base of lamp L. These contact ferrules are separated from one another by the base of the lamp which comprises a plug of insulating material 26 tapered at its outer end, as shown at 27, to facilitate the insertion of the lamp between the contact surfaces 9 which are normally biased toward each other by the spring tension of the contact blades. The contact surfaces 9 are held apart a predetermined distance by a separator 28 which is formed of insulating material, such as a molded plastic, and which is provided with arms 29 for insertion through openings 30 formed in the contact blades 8. In assembled position, the contact blades are biased inwardly against the outer edges of the separator 28 so that the contact surfaces 9 are spaced apart a distance sufficient to permit easy insertion of the guide plug 26 when the indicating lamp is to be mounted in position. As long as the lamp base is positioned to present the

tapered surface 27 to the contact blades, the lamp may be easily seated in position with the ferrules 25 in engagement with the contact blades, in the manner shown by Fig. 2. The width of the plug 26 is such, however, as shown by Fig. 3, that if the lamp is turned to a position so that the ferrules will not engage the contact blades, the plug will engage the ends of the contact blades so that the lamp cannot be inserted in position. This means that it is impossible to mount the lamp in position incorrectly.

The contact blades and lamp L are electrically isolated from the metal supporting tube 1 by a liner 31 of insulating material, such as an impregnated fiber, which extends the full length of the tube 1. A sleeve 31' of similar insulating material is located within the liner to assist in centering the lamp in position.

The resistance R which cooperates with the lamp L is likewise supported on the tube 1. The resistance comprises a winding 32 of any suitable resistance wire upon a shell 33 of insulating material, such as a ceramic sleeve. One end of the resistance wire is connected to a terminal 34 formed of a strip of metal wrapped around the shell and provided with a terminal screw 35; the other end of the resistance wire is connected by a heavy conducting lead 36 to one of the terminals 10 of a contact blade 8. The resistance wire, terminal strip 34 and lead wire 36 are secured in position on the shell 33 by a heavy coating of insulating material, such as a vitreous enamel. The resistor is assembled in position on the mounting tube 1 by sliding it over the end of the tube into engagement with the end cap 3 against which it is locked in position by a lock nut 37, the lock nut being insulated from the sleeve by a washer 38 of insulating material, such as sheet fiber. Alternatively, the resistor may be mounted in position prior to assembly of the end cap and contacts by placing it over the tube against the lock nut 37 and then assembling the cap 3 in position.

The receptacle is provided with an end cap 39 which is formed of translucent material, such as glass or a suitable plastic, so that the lamp L is visible from any point at the front of the panel board. The cap may be colored to give a designation of the circuit to which the indicating device is connected. The end cap is screw threaded, as indicated at 40, into what might be termed an escutcheon nut 41 which in turn is screw threaded to the supporting tube 1, as shown at 42. A portion of the colored cap 39 extends into the interior of the insulating sleeve 31, as shown at 43, so that the metal supporting tube 1 is completely insulated throughout its length. Prior to closing the end of the supporting tube by the escutcheon nut 41, a lock nut 44 is threaded onto the end of the tube and is spaced from the escutcheon nut to receive a panel board 45. The lock nut 44 may be adjusted laterally along the length of the tube between the other lock nut 37 and the escutcheon nut 41 to accommodate various sizes of mounting panels.

In mounting the device on the panel, the lock nut 44 is first adjusted approximately in accordance with the thickness of the panel on which the receptacle is to be mounted and then the escutcheon nut 41 is removed from the mounting tube 1 so that the latter may be inserted through an opening drilled in the panel board. Thereafter, the escutcheon nut 41 is replaced on the tube and the lock nut 44 tightened up against the back of the panel to fasten the receptacle in

position. In mounted position, the indicating lamp is visible from all points in front of the panel while the resistor and wiring to the receptacle are hidden out of sight behind the panel.

5 The indicating lamp may be easily replaced simply by removing the cap 39 and inserting a new lamp into contact with the blades 8. This may be done without disturbing the mounting of the receptacle on the panel. The lamp cannot be pushed into the tube too far since the base 26 will engage the separator 28 to adjust the lamp to correct mounted position, as indicated by Fig. 2.

15 My receptacle is one which is rugged in construction since it provides a single mounting support for both the resistor R and the lamp L on the metal tube 1. The length of the tube may be varied at will to accommodate the receptacle to a wide variety of panel board thicknesses and resistor lengths. The same results can be attained within the limits of the tube length by adjusting the lock nuts 37 and 44. The entire length of the resistor is supported on the tube so that there is no danger of breakage due to 20 accidental contact therewith. Moreover, the lamp is totally enclosed within and protected by the tube 1. The construction is such that the receptacle is not subject to breakage by vibration or shock.

25 The receptacle is connected into a circuit simply by running lead wires to the terminal 34 and one of the terminals 10. Since the lead wire 36 of the resistor is secured to the other terminal 10, the lamp and resistor will be connected in series according to the circuit diagram of Fig. 6.

30 What I claim as new and desire to secure by Letters Patent of the United States is:

1. In a receptacle for a switchboard lamp, a tube, a cap of insulating material closing one end of said tube, spaced contact members carried by said cap and having contact surfaces extending into the interior of said tube and being provided with terminal portions located outside said tube, a sleeve of insulating material surrounding said 35 tube, a resistor for connection to a terminal portion surrounding and supported on said sleeve, and means for mounting said tube on a support, said contact surfaces being adapted to supply current to a lamp inserted in the other end of said tube.

2. In a lamp receptacle, a tubular member, a cap of insulating material closing one end of said tube, spaced contact members carried by said cap extending into the interior of said tubular member and being provided with contact surfaces for making electric contact with a lamp inserted in the other end of said tubular member, a sleeve of insulating material surrounding a portion of said tubular member, and a resistor for electrical connection with one of the contact members being carried by said sleeve.

3. In a lamp receptacle, a metallic supporting tube, a cap of insulating material closing one end of said tube, spaced contact members carried by said cap extending into the interior of said tube and being provided with contact surfaces for electrically contacting a lamp to be inserted in the other end of said tube, a liner of insulating material disposed in said tube and insulating said contact members from said tube, and a resistor carried by said tube and being supported throughout its length thereby.

4. In a lamp receptacle, an externally threaded tubular member, a cap threaded on one end of said member, spaced contact members carried by

said cap extending into the interior of said member and being provided with contact surfaces for electrical connection to a lamp to be inserted in the other end of said member, a sleeve of insulating material surrounding a portion of said tubular member, a resistor carried by said sleeve for series connection with one of said contact members, and a lock nut threaded on said tubular member and forcing said sleeve against said cap.

5. In a lamp receptacle, an externally threaded tubular member, a cap threaded on one end of said member, spaced contact members carried by said cap and extending into the interior of said member and being provided with contact surfaces for electrical connection with a lamp inserted in the other end of said member, a sleeve of insulating material carrying a resistor surrounding a portion of said tubular member, means threaded on said tubular member and clamping said sleeve against said cap, and means

for closing the other end of said tubular member including a cap of translucent material.

6. In a lamp receptacle, an externally threaded tubular member, a cap threaded on one end of said member, spaced contact members carried by said cap extending into the interior of said member and being provided with contact surfaces for electrical connection with a lamp to be inserted in the other end of said member, a sleeve of insulating material surrounding a portion of said tubular member, a resistor carried by said sleeve for series connection with one of said contact members, a lock nut threaded on said tubular member and clamping said sleeve against said cap, means for closing the other end of said tubular member including a cap of translucent material, and means for mounting said tubular member in an opening in a support with the translucent cap on one side of said support and the resistor on the other side.
